FURNACE REFRACTORY SUPPORT

Charles E. Towner, Oak Lawn, Ill., assignor to
Crane Co., Chicago, Ill., a corporation of Illinois

Application November 23, 1944, Serial No. 564,871

6 Claims. (Cl. 158—4)

1

This invention relates to a refractory support or the like, and more particularly it applies to a refractory support for use with such heating devices as boilers or furnaces employing vaporizing oil burners, or with other types of burners employing gas or stoker feed and similar fuel media.

This invention applies particularly to an installation in which the type of boiler or furnace with which the device is associated is restricted at its lower portion to relatively small clearances and wherein the overhead space provided is likewise at a premium. In the latter connection in order to obtain a greater appreciation of the contribution made by this invention, it should be realized that previously with the removal of a vertically mounted oil burner for purposes of inspection or repair, the former methods of making oil burner installations, for example, required at least 3" clearance below the burner to allow for such removal. However, in contrast to the requirement just referred to with the sectional type of novel refractory support as hereinafter described in greater detail, the oil or other type of burner can be removed horizontally and with little or no clearance provision for such removal. The latter convenient method of removal also avoids the usual damage or breakage to the refractory when the burner is removed for repair or inspection. In the present invention the proposed refractory support is positioned and formed so as to minimize the damage thereto when the burner is removed.

A further important object of my invention is to provide a refractory support permitting complete access to the burner vaporizing pot without necessarily disturbing the refractory hearth.

A further object is to provide a refractory support in which the hearth formed therewith comprises preferably two or more sections, a larger section being suitable for attachment to a boiler or the like and with a smaller section attachable to the oil burner or other similar device.

Another object is to provide a device of the character described in which when it becomes necessary to remove the oil burner for reasons above mentioned, the oil line and power line may be simply disconnected and the burner can then be moved in a horizontal plane outwardly with the smaller hearth section attached thereto until the oil burner assembly is free of the boiler.

A further important object is to provide a hearth construction possessing such flexibility so as to be capable of being applied to either round or square boilers or furnaces.

2

Further important objects and advantages will become more readily apparent in connection with a reading of the following description read in light of the accompanying drawings, in which

Fig. 1 is an exterior perspective view of an oil burner unit embodying the novel refractory support of my invention, and with the unit almost entirely withdrawn from the boiler.

Fig. 2 is a view of the refractory detached from the boiler and showing the hearth and burner in operative position.

Fig. 3 is an exterior perspective view of the novel sectional frame for support of the refractory.

Similar reference characters refer to similar parts throughout the several views.

Referring now to Fig. 1 in which a lower exterior fragmentary view of a boiler 1 is shown, the lower wall of the boiler is provided with a recess or cut-out wall opening 2 below which the refractory hearth support generally designated "A" is mounted and through which the central portion of the burner moves. The burner is connected to the movable refractory element, the means of attachment being hereinafter described. The novel hearth structure of this invention consists essentially of two parts, one of which is stationary and the other movable. The larger stationary portion which is fitted in abutting relation with the lower portion of the boiler is substantially of circular form and is designated 3, but its shape will vary in accordance with the device with which it cooperates. A smaller element 4 is associated with a burner unit and moves transversely within the larger element 3. The larger section 3 is fixedly attached to the boiler and the smaller section is attached to the burner pot, the burner assembly being generally designated 5. The burner and controls are preferably mounted on a common draft tube 6 for the air supply, as indicated, the draft tube being fixedly attached to a lower portion of the burner assembly 5 so as to be movable together as a unit. In order to accomplish such convenient movability as hereinafter explained in greater detail, the burner unit 5 is preferably provided with the conventional electrical line connections indicated and with the fuel supply connection 7 for attachment to an oil feed line (not shown) all of which may be easily disconnected when it is necessary to move the burner outwardly from the boiler 1. As shown more clearly in Fig. 2, the frame 3 and its complementary smaller frame 4 are suitably filled with a refractory 8 forming the completed bottom hearth, when assembled,

for the burner, the refractory being molded or applied in the usual manner to fill the respective hollow portions of the frames 3 and 4. The relatively smaller frame section 4 is slideable within the stationary frame member 3 by means of the flanged guide 10 and is supported by the draft tube upon which the burner 5 and its indicated controls are mounted. The attachment of the smaller movable frame section of the refractory 8 to the burner pot is accomplished by means of suitable bolts (not shown) engaging the flanges 9 and thereby drawing the hoop 11 securely around the neck flange 12 of the burner, as shown in Fig. 1.

In order to close the aperture or cut-out wall opening 2 in the boiler, it may be desirable to provide an arcuately extending upwardly projecting shoulder portion 13 in the refractory 8 as indicated, to fill the opening 2 of the boiler when the burner is in the operating position shown in Fig. 2. However, it is clear that this construction will vary depending upon the type of boiler employed. Above the level of the flange 12 the boiler is generally provided with the inspection or access door opening 20 which is normally closed by a hinged door (not shown). Thus it is clear that the respective frame sections 3 and 4, when assembled, form the bottom portion of the fire chamber of the boiler. The outer end shoulder portion 13 fills the recess or cut-out wall opening 2 of the boiler, the latter recess being made sufficiently high to permit the upper part of the burner pot to pass through into the boiler fire chamber. The boiler is suitably supported on legs, not shown, the space between the floor and the bottom of the boiler being sufficient to establish clearance to allow for horizontal movement of the unit 5 when being withdrawn. The combined burner unit 5 and the draft tube 6 may be provided with the supporting adjustable legs 14 to permit of a nice adjustment with the fire chamber of the boiler and a close fit between the shoulder 13 and the recess 2.

As more clearly shown in Fig. 3, it is apparent that the hearth refractory support mounting 15 is relatively simple and sturdy and the side guide extension 16 allows for easy and accurate movability when it becomes necessary to inspect or to repair the burner unit 5. In small boilers in which clearances are held to relatively small dimensions the advantages of this construction will be quite obvious. It should also be understood that the detailed form and the manner in which the support is provided may vary substantially depending upon the type of installation used, and I desire therefore to be limited only to the scope of the appended claims.

I claim:

1. A hearth structure of the character described, in combination with a primary heat generator having a wall defining the sides of a combustion chamber and having an opening at the lower portion thereof, and a burner unit, the said hearth structure including fixed and movable frame-like portions, the said movable portion moving with said burner unit and being movable transversely relative to the fixed portion of the hearth structure, the movable portion and the fixed portion of the hearth structure cooperating to close the said opening at the lower portion of the combustion chamber, the said movable frame-like portion being formed at an end to receive the burner unit and to fit snugly within the fixed frame-like portion.

2. A hearth structure in combination with a

primary heat generator having a wall defining the sides of a combustion chamber with an opening at the lower portion thereof, a burner unit, the said hearth structure including a fixed frame portion with a wall cut-out portion and a movable frame-like member, the fixed frame portion having a cut-out central portion open at one end, the movable frame-like member being movable within the cut-out central portion and the opening at one end of the said fixed frame portion cooperating with said burner unit whereby both the frame-like member and said burner unit are movable transversely relative to the fixed frame portion of the hearth structure, the frame-like movable member and the fixed frame portion of the hearth structure cooperating with the said burner unit to close the said opening at the lower portion of the combustion chamber, the said movable frame-like member having an outer end portion upwardly extending to close said cut-out portion in the wall of said fixed frame portion of the hearth structure when the said movable frame-like member is received within the cut-out central portion and the open end of the said fixed frame portion of the said hearth structure.

3. The combination including a primary heat generator having a wall defining the sides of a combustion chamber and having a cut-out wall opening at the lower portion thereof, a hearth structure comprising a plurality of frames, one of said frames being movable, the other frame being fixed, a burner unit therefor, the movable frame being movable with the said burner unit and being adapted to move transversely and horizontally relative to the fixed frame of the said hearth structure, the said fixed frame, the said movable frame, and the said burner unit cooperating when assembled to define the lower limits of the combustion chamber.

4. A hearth structure of the character described, in combination with a primary heat generator having a wall defining the sides of a combustion chamber and having a cut-out wall opening at the lower portion thereof, the said hearth structure comprising a plurality of frames, one of said frames being fixed, a movable burner unit, the other of the said frames being movable with said burner unit, the said latter frame being adapted to move transversely relative to a fixed frame of the said hearth structure, the said fixed frame, the movable frame, and the burner unit cooperating to define the lower limits of the combustion chamber, the said movable frame being movable transversely within the fixed frame, and supporting means jointly carrying the said burner unit and the said movable frame when the movable frame is moved relative to the said fixed frame.

5. A hearth structure of the character described, in combination with a primary heat generator having a wall defining the sides of a combustion chamber and having an opening at the lower portion thereof, and a burner unit, the said hearth structure including a stationary frame and a movable frame member, the latter frame member having an outer shoulder portion, the said movable frame member cooperating with said burner unit and being movable transversely relative to the stationary frame member of the hearth structure, the outer shoulder portion of the movable frame member and the stationary frame member of the hearth structure cooperating to close the said opening at the lower portion of the combustion chamber and also define its inner lowermost limits, the said movable

frame member having side extension means slidably engageable with the said stationary frame of the hearth structure, the said stationary frame and the movable frame member having adjoining relieved portions therebetween forming when assembled an aperture to receive at least a portion of the said burner unit.

6. A hearth structure of the character described, in combination with a primary heat generator having a wall defining the sides of a combustion chamber and having an opening at the lower portion thereof, the said hearth structure comprising a plurality of stationary and movable frames, the movable frame having an upwardly extending outer shoulder portion, a burner unit, 15 one of the said frames cooperating with said burner unit to the extent of being movable with the said burner unit and being adapted to move transversely relative to the stationary frame of the said hearth structure, the respective stationary frame, the movable frame, and the burner unit cooperating to close said opening at

5
6
the lower portion of the combustion chamber, the burner unit being connected to the movable frame and being movable therewith in a horizontal plane within a relieved portion of the said stationary frame.

CHARLES E. TOWNER.
